DESIGN FOR A FISH LURE

Louis D. Adam, Ponca City, Okla., assignor to
The American Fork & Hoe Company, Cleveland, Ohio, a corporation of Ohio

Application June 28, 1941, Serial No. 101,774

Term of patent 3½ years

To all whom it may concern:

Be it known that I, Louis D. Adam, a citizen of the United States, residing at Ponca City, in the county of Kay and State of Oklahoma, have invented a new, original, and ornamental Design for a Fish Lure, of which the following is a specification, reference being had to the accompanying drawing, forming a part thereof, in which:

Fig. 1 is a side elevational view of a fish lure showing my new design;

Fig. 2 is a top plan view of the fish lure of
Fig. 1; and

Fig. 3 is a bottom plan view of the fish lure of
Fig. 1.

I claim:

The ornamental design for a fish lure, substantially as shown.

LOUIS D. ADAM.
